UNITED STATES PATENT OFFICE.

WILLIAM D. LIZABIACH, OF HOT SPRINGS, ARKANSAS.

RURAL-MAIL DELIVERY.

1,127,040.

Specification of Letters Patent.

Patented Feb. 2, 1915.

Application filed May 19, 1914. Serial No. 839,586.

To all whom it may concern:

Be it known that I, WILLIAM D. LIZABIACH, a citizen of the United States, residing at Hot Springs, in the county of Garland and State of Arkansas, have invented new and useful Improvements in Rural-Mail Delivery, of which the following is a specification.

The invention relates to an improved mail collection and delivery system, designed for the collection of mail from and distribution of mail to a series of separated point, as in rural delivery, said points having connection through the system with a main station.

The main object of the present invention is the provision of a system including track wires or rods, and a carrier suspended therefrom and adapted for travel thereover, the carrier being provided with mail collecting and distributing elements, whereby the mail may be collected from or distributed to any predetermined point or station throughout the length of travel of the carrier.

The invention in the preferred form of details will be described in the following specification, reference being had particularly to the accompanying drawings, in which:

Figure 1 is a view in side elevation of the improved carrier, showing the same in place on the tracks. Fig. 2 is a similar view taken from the opposite side. Fig. 3 is an end elevation of the same. Fig. 4 is a vertical central longitudinal section through the carrier. Fig. 5 is a transverse section taken through the device.

Referring particularly to the accompanying drawings, the improved system includes trackway preferably in the form of trolley wires 1 and 2 forming circuit wires therein from any suitable source of supply and arranged throughout the area over which the system is designed to operate.

The improved carrier comprises a casing 3 preferably metallic, having one end formed with an opening 4 extending from the top of the casing to a point some distance above the bottom thereof, the opening being designed to be closed by the hinged door 5. The bottom of the casing is formed with an opening 6 for a portion of its length adapted to be closed by doors 7 hinged at the side edges and meeting the longitudinal center of the opening. The

edges of the opening are provided with limiting strips 8 adapted to limit the outward movement of the doors and support the same in opening closing position. Springs 60 9 are arranged in rear of the doors to force them to closing position, trips 10 being arranged in the side walls of the casing to engage the doors and hold them fully open against tension of the springs 9. Brackets 65 11 are secured to the bottom surface of the top of the casing and arranged in opposing relation, a trackway 12 being supported upon the brackets in a manner to provide an uninterrupted upper edge of said track. 70 The ends of the track are arranged in spaced relation to form an open space 13, brackets 14 supporting such ends of the trackway. Supporting wheels 15 are rotatably mounted in spaced relation within 75 the plane of the trackway, said wheels having flanges on their lower edges. A carrier ribbon 16 of endless type is supported for endless travel upon the wheels, the arrangement being such that the ribbon 16 is approximately in the same horizontal plane as the trackway. Carrier rods 17 project outwardly in uniformly spaced relation from the ribbon 16, said pins including sections fixed to the ribbon and supporting 80 sections 18 pivotally connected to the fixed sections, the pins as a whole being of such length that the ends of the movable sections 18 are adapted to rest upon the upper edge of the track 12, the hinged connection between the sections of the pins being arranged between the ribbon and track. 85 On the top edge the ribbon 16 is formed to provide a series of ratchet teeth 19, and the angle pawl 20 is adapted to cooperate successively with said teeth. The teeth are so arranged, and the movement of the pawl is such that the ribbon is moved approximately the difference between the adjacent pins at each operation of the pawl. The pawl is 90 held in engagement with the ratchet teeth by the spring 21, and is connected to the arm 22 projecting radially from the shaft 23, which latter extends to one side wall of the casing and is connected to the trip rod 100 24 having its free end operative in the guide 25 secured to the carrier. A spring 26 is adapted to return the rod 24 to normal position, that is retract the pawl for engagement with the next successive tooth of the 105 ribbon.

On that side of the casing opposite the

rod 24 is pivotally supported a lever 27 having its lower free end mounted in a guide 28 and its upper end connected through the medium of a rod 29 with the door 5, a spring 30 operating lever in that portion, which, will cause the same to close the door 5.

The casing is movably supported upon the track wires through uprights 31 carrying grooved wheels 32. One opposing set of wheels are rigidly connected to the shaft or axle 33 which through the medium of sprocket wheels and chains 34 is driven by motor 35, current being led to the latter through conductors 36 fed through the opposing pair of trolley wheels which are suitably insulated for the purpose. The conductors 36 lead through reversing switch 37 having a handle portion thereof in position to be operated by the trip at each end of the system, so that the travel of the carrier in the relatively reverse directions is automatically controlled.

In use, in the operation of the improved system, the carrier is designed to deliver mail during one trip lengthwise the track and to take up mail during the return trip. In arranging for the delivery trip the respective mail matter designed for the successive stations is supported by loops upon successive pins 17, being arranged upon movable section thereof and the latter is then arranged upon a track 12 so as to support the material pendant therefrom between the track and ribbon. As the carrier advances a suitably arranged trip mounted upon a fixture adjacent the station engages and actuates the bar 24 with the effect to advance the ribbon one step. This carries the pin on which the mail matter for that particular station is suspended in line with the space 18, whereupon the free end of the pin drops, permitting the mail to drop to the bottom of the carrier and through the doors 7 which have been previously locked open through

Washington, D. C."

coöperation of the trips. The mail matter for each station is thus delivered. On the return trip the mail matter to be taken up, which is supported in any suitable type of frame, is received through the opening 4, the door 5 having been opened for such reception through a suitable arranged trip engaging and operating the lever 27. At the end of the delivery trip the doors 7 are released to the influence of the springs 9 and 51 closed.

What is claimed is:—

1. A mail delivery and collection apparatus including a trackway, a casing traveling lengthwise thereof, an endless ribbon mounted for movement in the casing, means for operating said element, mail supporting pins projecting from the element and constructed in pivotally connected sections, and an interrupted trackway for coöoperating with the pivoted end of said pins except at predetermined point, said casing being formed with receiving opening and a door for closing said opening, and means for operating the door. 70

2. A mail delivery and collection apparatus including a trackway, a casing traveling lengthwise thereof, an endless ribbon mounted for movement in the casing, means for operating said element, mail supporting pins projecting from the element and constructed in pivotally connected sections, an interrupted trackway for coöoperating with the pivoted end of said pins except at predetermined point, said casing being formed 75 with a delivery opening, doors closing said opening, means for moving the doors to closed position, and means for locking the doors against such closing means. 80

In testimony whereof I affix my signature 85 in presence of two witnesses.

WILLIAM D. LIZABIACH
